UNITED STATES PATENT OFFICE.

HERBERT H. HEWITT, OF BUFFALO, NEW YORK.

SIDE FRAME FOR CAR-TRUCKS.

1,186,987.

Specification of Letters Patent. Patented June 13, 1916.

Application filed May 22, 1911. Serial No. 628,800.

To all whom it may concern:

Be it known that I, HERBERT H. HEWITT, a citizen of the United States, residing at Buffalo, in the county of Erie, State of New York, have invented certain new and useful Improvements in Side Frames for Car-Trucks, of which I do declare the following to be a full, clear, and exact description, reference being had to the accompanying drawing, forming part of this specification.

The present invention has for its object to produce a simple, strong and effective construction of car truck which can be readily and cheaply manufactured and which will combine maximum of strength with minimum of weight.

The invention consists in the features of novelty hereinafter described, illustrated in the accompanying drawing and particularly pointed out in the claims at the end of this specification.

Figure 1 is a view illustrating the preferred manner of forming my improved side frame. Fig. 2 is a view in side elevation of the finished side frame. Fig. 3 is a view in longitudinal section on line 3—3 of Fig. 2.

While the improved side frame herein-after described has features which may be advantageously used, even if the side frame be made of cast metal, the main purpose of the invention is to enable a side frame to be made from flat bars of ductile iron or steel of commercial sizes, in which form the metal can be manufactured more cheaply than when rolled in special shapes.

In the preferred manner of carrying out my invention, the side frame is formed from flat bars of iron or steel which are first cut to proper length, are then bent cold around forms of proper shape and the parts are then assembled and welded together at the contact points by electricity, by acetylene gas flame or any other suitable manner. After the parts have thus been welded they will be placed in a furnace and brought to a welding heat and finally removed to a powerful press, where between suitable dies the metal will be squeezed to effect such proper disposition of the metal as to give to the side frame the desired form, as will hereinafter more fully appear. In Fig. 1 of the drawing I have shown the parts to comprise the side frame cut, bent to proper shape, and assembled ready for the welding operation. In the process of welding, small pieces of metal may be added about the

points of contact of the several bars, these pieces of metal fusing under the welding heat and combining with the bars at such points.

While my invention may be applied in the production of other designs than the precise construction of side frame illustrated in the accompanying drawing, the invention is more especially intended for producing a side frame for car trucks of the type set forth in Letters Patent of the United States No. 1,009,747, granted to me November 28, 1911. The side frames of the car truck set forth in said Letters Patent No. 1,009,747 have end portions formed with circular journal boxes and with central openings wherein will be journaled the ends of the transom that extend between the side frames.

In the accompanying drawing, the side frame is shown as comprising annular end portions 5 and an annular central portion 6, the annular end portions 5 being designed to receive the journal boxes for the car axles of the truck and the annular central portion 6 being designed to receive one end of the transom that will connect the side frames of the truck. The annular end portions 5 and the annular central portion 6 are connected together by the diagonally disposed truss bars 9. One of the longitudinal bars 7 or 8, (and by preference the upper bar 7) has its ends welded to the annular end portions 5, while the opposite longitudinal bar, (preferably the lower bar 8) is by preference formed integral with the bar from which the greater portion of the annular end portions of the side frame are formed. Preferably, also, the diagonal truss bars 9 are formed from the same bar of metal that extends around the ends and forms the major part of the annular end portions of the side frame.

The preferred method of forming my improved side frame consists in cutting a flat bar of ductile metal to proper length to form not only one of the longitudinal bars (preferably the bar 8) of the finished side frame, but sufficiently long, also, to form the major parts of the annular end portions 5 and the diagonal truss bars 9 of the finished side frame, this bar being bent as shown in Fig. 1 of the drawing. Another bar 7 of corresponding cross section will be cut of proper

length to extend between the annular end portions 5, as shown in Fig. 1. Short segmental bars 5^a and 6^a of similar cross section will be cut to proper length and bent in segmental form and will be placed in the position shown in Fig. 1 of the drawing. The several bars will then be welded together at their points of contact by electricity, by an acetylene gas flame or in any other suitable manner, and by preference, small portions of metal will be placed about the points of contact of the several bars, these portions of metal becoming fused and uniting with the bars in the welding operation. In this way the several bars illustrated in Fig. 1 of the drawing, will be securely welded together. The skeleton frame thus formed will then be placed in a heating furnace and brought to a welding heat and from the furnace will be transferred to a powerful press and will be squeezed between dies of proper shape, which will reduce the width of the bars and cause them to be thickened somewhat toward the center, in order to give to the finished frame substantially the configuration shown in Figs. 2 and 3 of the drawing. A small excess of metal beyond that used in the finished frame will be supplied, this excess being squeezed out as fins between the dies at the middle of the bars composing the side frame, these fins being later removed by proper tools in the finishing operation. The operation of heating and pressing the skeleton frame between dies not only insures a perfect weld of all the parts, but also most effectively distributes the excess metal forming the fillets at the points where the welds are made, as clearly shown in Fig. 2 of the drawing.

In the form of the invention shown, the lower longitudinal bar 8 having truss bars 9 formed integral therewith, constitutes the tension member and the upper bar 7 constitutes the compression member, and the fiber 45 of the metal extends in the direction of the severe strain exerted upon the bars. Either of the bars 7 or 8 may be made somewhat heavier if found necessary to resist the strains, and indeed the thickness and relative proportion of the bars may be varied without departing from the spirit of my invention. The sides of the annular central portion of the side frame obviously constitute most effective braces between the tension and compression members and the finished side frame may be used either in the position shown or may be reversed, if desired.

So far as I am aware, my invention presents the first instance of a side frame formed of bent bars of ductile metal welded together to give the desired shape to the finished frame, which feature may obviously be employed in various forms of side frames, other than the specific form illustrated in

the accompanying drawing. My invention also presents the first instance of a side frame embodying the specific features of construction above set out and offers the first instance in which a side frame has been formed by cutting ductile metal bars to proper length, then bending said bars to proper shape and welding said bent bars together, in order to give the required shape and disposition of the metal to the finished side frame.

Having thus described my invention what I claim as new and desire to secure by Letters Patent, is:

1. A side frame for car trucks having open end portions adapted to receive the journal boxes, upper and lower longitudinal bars extending between said open end portions, the several parts of said side frame comprising wrought metal bars welded together and shaped under pressure to form an integral structure.

2. A side frame for car trucks having open end portions adapted to receive journal boxes, and an open central portion, upper and lower longitudinal bars connecting said end and said central portions, the several parts of said side frame comprising wrought metal bars welded together and shaped under pressure to form an integral structure.

3. A side frame for car trucks comprising open ended portions adapted to receive the journal boxes, an open central portion and upper and lower longitudinal bars connecting said end and central portions at top and bottom, said side frame having also diagonal bars extending from the lower portion of the central opening to the upper portions of the end openings, the several parts of said side frame comprising wrought metal bars welded together to form an integral structure.

4. A side frame for car trucks comprising annular end portions adapted to receive journal boxes, an annular central portion and top and bottom bars connecting said several annular portions.

5. A side frame for car trucks comprising annular end portions adapted to receive journal boxes, an annular central portion, longitudinal bars connecting said several annular portions at top and bottom and diagonal bars upon opposite sides of said central portion and extending therefrom to the annular end portions.

6. A side frame for car trucks comprising open end portions adapted to receive journal boxes, an open central portion, longitudinal bars connecting said end and central portions, and diagonal bars upon opposite sides of said central portion and extending therefrom to the open end portions, said diagonal bars being formed integral with one of said longitudinal bars.

7. A side frame for car trucks comprising

ing annular end portions formed from bent bars, upper and lower longitudinal bars extending between said annular end portions one of the longitudinal bars being formed integral with said annular end portions.

8. A side frame for car trucks comprising annular end portions adapted to receive journal boxes, said end portions being formed of bent bars, longitudinal bars connecting said end portions at top and bottom, diagonal bars extending from said annular end portions toward the center of the frame and connections between the inner ends of said diagonal bars and one of said longitudinal bars.

9. A side frame for car trucks comprising open end portions adapted to receive journal boxes, longitudinal bars connecting said open end portions at top and bottom, and bars extending diagonally inward from the outer parts of said end portions toward the center of the frame, and braces extending between the inner ends of said diagonal bars and the longitudinal bar farthest therefrom, said several parts being formed of bent bars of metal.

10. A side frame for car trucks comprising open end portions adapted to receive journal boxes, an open central portion to receive a transom, top and bottom bars connecting said end and central portions, diagonal bars connecting the outer sides of said open end portions to the opposite sides of the open central portion, said several parts being formed of bent metal bars and said diagonal bars being formed integral with one of the bars that comprise the open end portions of the frame.

11. A side frame for car trucks comprising open end portions adapted to receive journal boxes, an open central portion to receive a transom, and longitudinal bars connecting said several portions at top and bottom, each of said end portions being composed in part of a bent bar integral with one of said longitudinal bars.

12. A side frame for car trucks comprising annular end portions adapted to receive journal boxes, an annular central portion to receive a transom, and longitudinal bars connecting said several annular portions at top and bottom, said central annular portion being composed in part of said longitudinal bars and in part of segmental bars welded thereto.

13. A side frame for car trucks comprising annular end portions, and longitudinal bars connecting said annular end portions at top and bottom, said annular end portions and said longitudinal bars being formed of ductile metal and the outer walls of said annular end portions being formed integral with one of said longitudinal bars.

14. A side frame for car trucks comprising open end portions, an open central portion, top and bottom longitudinal bars connecting said end and central portions, diagonal bars extending between said end portions and one of said longitudinal bars and short bars forming parts of said end and central portions, said several bars being welded together.
